T. KERNER,
HOPPER DOOR FOR REFUSE INCINERATORS.
APPLICATION FILED AUG. 1, 1917.

1,297,360.

Patented Mar. 18, 1919.

UNITED STATES PATENT OFFICE.

THEODORE KERNER, OF MILWAUKEE, WISCONSIN.

COPPER-DOOR FOR REFUSE-INCINERATORS.

1,297,360.

Specification of Letters Patent.

Patented Mar. 18, 1919.

Continuation in part of application Serial No. 864,233, filed September 30, 1914. This application filed August 1, 1917. Serial No. 183,994.

To all whom it may concern:

Be it known that I, THEODORE KERNER, a citizen of the United States, residing at Milwaukee, in the county of Milwaukee and State of Wisconsin, have invented certain new and useful Improvements in Hopper-Doors for Refuse-Incinerators, of which the following is a specification, reference being had to the accompanying drawing, forming 10 a part thereof.

This application is in part a substitution for and continuation of my application Serial No. 864,233, filed September 30, 1914.

The invention relates more particularly to 15 closures and receiving and feeding hoppers for garbage or refuse incinerators, especially such as to utilize an ordinary chimney flue as a conduit for the garbage or refuse into a cremating chamber at the lower end of the flue 20 as well as a smoke and ventilating flue for said chamber.

Its main objects are to facilitate the disposal of garbage, refuse and the like; to provide a convenient, neat and effective closure 25 for a lateral opening into a chimney flue and refuse conduit; to facilitate installation of the device; to avoid defacing or injuring finished parts of the device which are exposed; to maintain a tight closure into the 30 chimney flue and refuse conduit and thereby prevent the escape of smoke and odors therefrom through the hopper door opening; and generally to improve the construction and operation of devices of this class.

It consists in the construction, arrangement and combination of parts as herein-after particularly described and pointed out in the claims.

In the accompanying drawing like characters designate the same parts in the several figures.

Figure 1 is a vertical section on the line 1-1, Fig. 2, of a hopper door embodying the invention, the hopper being shown by full lines in its normal closed and discharging position, and by dotted lines in its abnormal open and receiving position; Fig. 2 is a front elevation of the device, a portion of the door plate and hopper being broken away; and 50 Fig. 3 is an enlarged cross section on the line 3-3, Fig. 1, of a part of the door plate, hopper and frame.

The device comprises a metal frame, which is made as shown in Fig. 1, in two parts or 55 sections, an inner part or section *a*, which is

adapted to be permanently set in a lateral opening into a chimney flue and refuse conduit, and an outer part or section *b*, which is fitted and adapted to be detachably and adjustably fastened to the inner part or section *a*. 60

The part or section *a* of the frame, which is of substantially quadrangular shape, has an inwardly and downwardly inclined bottom wall, parallel vertical side walls and a 65 top wall, and forms a lining for the opening into the chimney flue. The front edge of this part or section of the frame is set flush with the chimney face and serves as a ground for plastering. The top wall of the frame section *a*, the inner portion of which is preferably inclined slightly downward while the outer portion is disposed in a substantially horizontal plane at an angle to the inner portion, is inclined or beveled downwardly on 70 the under side adjacent to and toward its outer edge and is preferably formed on the upper side with anchoring ribs or projections *c*, and along its inner edge with an upwardly projecting flange *d*, which adds 75 strength to the frame section and helps to hold it firmly in place. The bottom wall of the frame section *a*, is preferably formed at or adjacent to its ends and inner edge and in or parallel with the planes of the side 80 walls, with downwardly projecting triangular wings or flanges *e*, which facilitate setting the frame section and lining in a chimney opening and also help to firmly hold it 85 in place therein. 90

The outer part or section *b* of the frame is formed with a flat marginal flange or rim *f*, which is adapted to bear against the outer edge of the frame section *a*, or the finished chimney face around it and to cover the joint 95 between said frame section and the chimney wall. Inside of the flange *f* it is formed with an outwardly projecting and downwardly and outwardly inclined door jamb or seat *g*. On the inner or back side along the lower 100 side of the opening therein, it is also formed with an inwardly projecting and downwardly inclined lip *h*, and along the upper side of the opening with an inwardly projecting flange or lip *i*, provided with screws 105 *j*. The lip *h*, which is in effect an extension of the inwardly and downwardly inclined bottom wall of the door jamb or seat, is adapted to be hooked over and engaged with the outer edge of the bottom wall of the 110

frame section *a*, as shown in Fig. 1, while the screws *j* in the flange or lip *i*, which fits freely into the opening in the frame section *a*, just below the top wall thereof, are 5 adapted to be turned up into engagement with the inclined or beveled under face of said wall adjacent to its outer edge, thereby securely, adjustably and removably fastening the frame section *b* to the permanently 10 set frame section *a*. This construction affords convenient and effective means for securing the outer frame section *b* in which the hopper door is pivotally mounted or hinged, to the inner permanently set frame section 15 *a*, with the rim *f* of the outer section bearing snugly against the chimney face, and allows for variation in the thickness of the plaster or its projection more or less beyond the outer edge of the frame section *a*, and for 20 inaccuracies in the setting of said frame section.

To prevent cracking of the plaster around the door frame as a result of the settling of the chimney or the expansion of the frame 25 due to heat from the chimney flue, the inner frame section *a* is provided with a yielding plaster-support *k*, which may extend completely or part way around it adjacent to its outer edge. It may be conveniently 30 made as shown, of a strip of sheet metal fastened adjacent to its inner edge by bolts or rivets *l*, to the frame section, and flanged or bent along its unsupported outer edge toward and substantially flush with the outer 35 edge of said frame section, which is recessed as shown in Fig. 1, to receive said flanged or bent edge and permit said support to yield toward the frame section, and the plaster resting or bearing thereon, to settle 40 or shift behind the overlapping rim *f*, or the frame to expand without cracking the plaster.

A door plate *m*, which like the parts or sections of the frame, may be made of cast 45 iron, is horizontally pivoted or hinged adjacent to its lower side to the lower and outer portion of the door jamb or seat *h* of the frame section *b*. This may be conveniently accomplished by means of bolts 50 or pins *n*, threaded in outwardly projecting ears *o* on the door jamb or seat and journaled in lug *p* on the inner side of the door plate, as shown. The door plate *m* is formed with a backwardly or inwardly curved marginal flange or rim, which is fitted to and 55 rests snugly against the jamb or seat *g* when the door is closed.

A hopper *q*, preferably constructed of a single piece of sheet metal, is attached by 60 bolts or rivets to the back of the door plate *m*, a sheet *r* of asbestos board or other suitable insulating material being interposed between the outer wall of the hopper and the door plate, to prevent the heating of said 65 plate and radiation of heat therefrom when

garbage or refuse is being burned in the furnace or chamber at the lower end of the chimney flue.

The inner or back wall of the hopper converging toward the front wall which is attached to the door plate *m*, forms with the parallel and approximately triangular side walls of the hopper a downwardly inclined chute into the chimney flue when the door is closed, as shown by full lines in Fig. 1. 70 When the hopper is tipped forward or outward into receiving position, as indicated by dotted lines in Fig. 1, the inner edge of the rear wall seats against the top wall of the frame section *a* and closes the hopper door 80 opening into the room or apartment with which it communicates.

The door plate *m* is formed along its lower edge to a segment of a cylinder concentric with the axis of the pivot bolts or pins *n*, and makes a close joint with the lower cross wall or member of the door jamb or seat *g* on the frame member *b* in any position of the door plate and hopper, 85 as shown in Fig. 1.

The sheet metal of which the hopper *q* is constructed, is cut and lapped as shown in Fig. 3, so that while the front wall is severed from the side walls which it overlaps, the back or inner wall is integral with the 95 side and front walls, and seamed joints which tend to rust and break and in which dirt lodges, are thus avoided.

The back or inner wall of the hopper is longer than the front wall or door plate 100 *m*, in a direction perpendicular to the pivot axis of the hopper, so that when the hopper is tipped forward or outward into receiving position, as indicated by dotted lines in Fig. 1, its back or inner wall will extend 105 obliquely upward across the opening into the chimney flue from the outer and lower part of the jamb or seat *g* on the frame section *b*, and by engagement with the inner and upper part of the frame section *a*, will 110 arrest and hold the hopper in that position and close the opening into the chimney flue, without obstructing the flue itself, and so that when the hopper is tipped backward or inward into discharging position, as shown by full lines, its back or inner wall will extend obliquely downward to the chimney flue at a sufficient pitch to insure the 115 discharge of the contents of the hopper into the flue.

The door plate is provided on the outer side adjacent to its upper edge with a handle *s*.

The frame being made in two separate 125 parts or sections *a* and *b*, which can be easily and quickly assembled and fastened together, admit of first setting the section *a* in a chimney when it is built or the incinerator is installed therein, and after the building is completed or the chimney is plastered 130

or finished, of installing the outer frame section with the hopper. In this way soiling, defacing or otherwise injuring the finished parts of the device such as the exposed faces 5 of the frame section *b* and of the door plate *m* while the building or chimney is being erected and finished, are avoided.

A hopper door constructed and installed as hereinbefore described in connection with 10 a chimney flue having a cremating furnace or chamber at its lower end, provides for the disposal of garbage and other refuse in a most convenient, cleanly and sanitary manner.

15 Various modifications in the details of construction and arrangement of parts may be made without departure from the principle and scope of the invention as defined in the following claims.

20 I claim:

1. A hopper door for refuse incinerators comprising a frame adapted to be set in and to line a lateral opening into a chimney flue and having an outwardly and downwardly 25 inclined door seat, and a hopper pivoted to said frame adjacent to the lower outstanding side of said seat and having a front wall forming a door which closes in an upwardly and inwardly inclined plane against said 30 seat, and side and back walls forming with the front wall an open top receptacle when the door is open, and an inwardly and downwardly inclined chute into the chimney flue when the door is closed, the back wall, 35 which is of greater length than the front wall transversely to the pivot axis of the hopper, seating against the top wall of the frame and closing the opening into the chimney flue when the hopper is tipped for 40 ward into receiving position.

2. A hopper door for refuse incinerators comprising a frame composed of two sections, an inner section adapted to be permanently set in and form a lining for a lateral 45 opening into a chimney flue and an outer section adapted to be detachably fastened to the outer side of the inner section, and a hopper pivoted adjacent to the junction of its front and back walls in the outer frame 50 section adjacent to its lower side and removable therewith from the inner frame section, the front wall of the hopper seating against the front frame section and closing the opening therein when the hopper is tipped inward into discharging position and the back wall of the hopper seating against the inner frame section, and closing the 55 opening into the chimney flue when the hopper is tipped outward into receiving position.

3. A hopper door for refuse incinerators comprising a frame composed of two sections, an inner section adapted to be permanently set in and form a lining for a lateral 60 opening into a chimney flue and having an

inwardly and downwardly inclined bottom wall and an outwardly and downwardly inclined face on the top wall adjacent its outer edge, and an outer section fitted to the front side of the other section and having an inwardly and downwardly inclined lip adjacent its lower side adapted to hook over and engage with the outer edge of the bottom wall of the inner section, and an inwardly projecting flange adjacent the upper side, 75 provided with screws adapted to adjustably engage said inclined face on the top wall of the inner section, and a hopper pivoted adjacent to the junction of its front and back walls in the outer frame section adjacent to its lower side and removable therewith from the inner frame section, the front wall seating against the outer frame section and closing the opening therein when the hopper is tipped inward and the back wall 80 seating against the upper part of the inner frame section and closing the opening into the chimney flue when the hopper is tipped outward.

4. A hopper door for refuse incinerators 90 comprising a frame composed of two sections, an inner section adapted to be set in and form a lining for a lateral opening into a chimney flue with its front edge approximately flush with the chimney face, and an 95 outer section fitted and adapted to be removably attached to the inner section and having a downwardly and outwardly inclined seat, and a hopper pivoted adjacent to the junction of its front and back walls 100 in the outer frame section adjacent to its lower side and removable therewith from the inner frame section, the front wall projecting at the top and sides beyond the side walls and closing against said seat when 105 the hopper is tipped inward and the back wall seating against the inner upper part of the inner frame section and closing the opening into the chimney flue when the hopper is tipped outward and forming with 110 the side walls an inwardly and downwardly inclined chute when the hopper is tipped inward.

5. A hopper door for refuse incinerators comprising a frame adapted to be set in a 115 lateral opening into a chimney flue and having an outwardly and downwardly inclined seat, a door plate pivoted horizontally to the outer and lower part of the frame and adapted to close against said seat, and a 120 one-piece sheet metal hopper attached to the back of the door plate and forming an inwardly and downwardly inclined chute into the chimney flue when the door is closed, the back wall of the hopper which is longer than 125 the front wall, engaging with the inner and upper part of the frame and closing the opening into the flue when the hopper is tipped outward into receiving position.

6. A hopper door for refuse incinerators 130

- comprising a frame adapted to be set in and form a lining for a lateral opening into a chimney flue and having an outwardly and downwardly inclined seat, a door plate pivoted horizontally to the outer and lower part of the frame and adapted to close against said seat, a sheet metal hopper attached to the back of the door plate and forming an inwardly and downwardly inclined chute into the chimney flue when the door plate is closed, the back wall of the hopper which is longer than the front wall, engaging with the inner part of the top wall of the frame and closing the opening into the flue when the hopper is tipped outward into receiving position, and a sheet of insulating material interposed between the door plate and the front wall of the hopper.
7. A hopper door for refuse incinerators comprising an inner frame section adapted to be permanently set in a lateral opening into a chimney flue and forming a ground for plastering the chimney face, a yielding plaster support attached to said frame section adjacent to its outer edge, an outer frame section detachably fastened to and overlapping the inner frame section and plaster support, and a hopper pivotally mounted in and removable with the outer frame section, the outer wall of the hopper closing the opening into the flue when the hopper is in discharging position and the inner wall

closing the opening into the flue when the hopper is in receiving position.

8. A hopper door for refuse incinerators comprising a frame composed of two sections, an inner section adapted to be permanently set in and form a lining for an opening into a chimney flue, the bottom wall of said frame section being formed on the under side with downwardly projecting triangular supporting and anchoring wings, and the upper wall of said frame section being formed on the upper side with an upwardly projecting reinforcing and anchoring flange, an outer frame section fitted and adapted to be adjustably and detachably fastened to the inner frame section and having a downwardly and outwardly inclined seat, and a hopper pivotally mounted in the outer frame section adjacent to the lower side of said seat and removable therewith from the inner frame section, the front wall of the hopper closing against said seat when the hopper is tipped inward into discharging position and the back wall of the hopper engaging with the upper and inner part of the inner frame section and closing the opening into the chimney flue when the hopper is tipped outward into receiving position.

In witness whereof I hereto affix my signature.

THEODORE KERNER.
